UNITED STATES PATENT OFFICE

168,325

MIRROR FRAME OR THE LIKE

George Abrams, Great Neck, N. Y.

Application June 20, 1952, Serial No. 20,292

Term of patent 14 years

(Cl. D29—20)

To all whom it may concern:

Be it known that I, George Abrams, a citizen of the United States of America and a resident of Great Neck, in the county of Nassau and State of New York, have invented a new, original, and ornamental Design for a Mirror Frame or the like, of which the following is a specification, reference being had to the accompanying drawing, forming a part hereof.

Figure 1 is a front elevational view of a mirror frame, showing my new design;

Figure 2 is a sectional view thereof taken on the line 2—2 of Figure 1;

Figure 3 is a fragmentary perspective view looking toward the upper left hand corner thereof.

The characteristic feature of my design resides in the combination on a mirror frame of the integral overhanging ovoid inner edge beading.

I claim:

The ornamental design for a mirror frame or the like, substantially as shown and described.

GEORGE ABRAMS.
